STOP MECHANISM FOR SEWING-MACHINES.

1,042,602.

Specification of Letters Patent.

Patented Oct. 29, 1912.

Application filed December 26, 1911. Serial No. 667,579.

To all whom it may concern:

Be it known that we, JOHN W. ROBERTS and ARTHUR P. BREWSTER, citizens of the United States, residing at Passaic, in the county of Passaic and State of New Jersey, have invented certain new and useful Improvements in Stop Mechanisms for Sewing-Machines; and we do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to a sewing-machine which is provided with a clutch, and comprises a machine having means thereon, which means is operated by the machine to cause the machine to stop when the thread breaks in the machine, or when the spool of thread is exhausted or when the thread in the shuttle is exhausted.

The mechanism consists of an apparatus, preferably operated from the needle bar, which apparatus disconnects the clutch when engaged thereby, but which engagement, under normal conditions, is prevented by the tension of the thread in the machine so that while the thread is under a tension, said tension being due to the thread not being broken or not being exhausted, the machine continues to operate without interruption.

This mechanism is particularly adapted for such machines as are used in numbers in a factory where one operator attends to a number of machines, and where sometimes a machine will still be running but feeding material therethrough without said material being sewed, such as for instance in the case of hemstitching machines, where one operator has a number of machines, and even under careful supervision a machine will sometimes operate for a considerable length of time without thread, thereby damaging material that passes through it, and at the same time not being productive, causing a loss of time and material.

The invention is illustrated in the accompanying drawing, in which—

Figure 1 is an end view of a sewing-machine equipped with our improved apparatus. Fig. 2 is a side view of one end showing the head and part of the arm of the machine, and Fig. 3 is a section through a sleeve carrying a finger employed in the device.

Any form of machine 10 can be used, and we do not limit ourselves to any particular type of machine, which machine has an arm 11 provided with a head 12 thereon, which head 12 has a reciprocating needle bar 13 therein which is provided with a needle 14 which reciprocates with the needle bar and passes in the usual way through a recess in a presser-foot 15.

The machine is operated from a fly-wheel 16 which is driven by a belt 17, which belt and fly-wheel are thrown into and out of operative connection by means of a clutch 18 which is simply shown in dotted outline in Fig. 1 so as to indicate it, since any kind of clutch can be employed, as will be evident.

So far as described none of the machine is new.

Our invention resides in the means for operating the clutch from the needle bar, which invention is as follows: On the needle bar 13 we arrange a tripping arm 19 which projects through a slot 20 in the head. Mounted on the frame of the machine is a sleeve 21 provided with a stud 22 on which the sleeve is adapted to swing, the sleeve being limited in its movement by stops 23, being held to the limit of its movement in one direction by a spring 25. Slidably arranged in the sleeve 21 is a finger 26 which is normally held yieldingly in its position by a spring 27. It will thus be seen that the finger is capable of both a longitudinal movement and a transverse movement. Suitably arranged on the sleeve is a thread guide 28. The thread is conducted from the spool 29 to a tension device 30 over the take-up arm 31 and through the thread guide 28, and then conducted over the guide 32 to the needle 14, and is fed through to

connect with the thread from the shuttle 33, which shuttle is simply shown in dotted outline and is not illustrated in detail, since any form of shuttle can be used, and it will be evident to any one skilled in the art how this shuttle operates and where it is located. The thread from the shuttle 33 combines with the thread from the spool after they have been knotted together by the operation 10 of the machine, so that a breaking of the thread or the exhausting of the tread from the spool or from the shuttle will cause the thread to lose its tension, and the sleeve 21 is held by the spring 25 in the position 15 shown in Fig. 1, and when the needle bar comes down the tripping arm 19 engages the top end of the finger 26 and pushes it down so that the lower end engages a lever 34 on a rod 35, the rod having a crank 37, 20 the pin 38 of which forces up the tripping arm 39, that is, swings the bar on its pivot 40 which in turn releases the pin 41 of the setting arm 42, and this in turn permits the 25 pin 43 of the clutch-operating arm 44 to permit said clutch-operating arm to be acted on by the spring 45, the arm 44 extending around and being shown in dotted lines adjacent to the clutch 18, the swinging of the arm 44 permitting said clutch to become disconnected and the machine stops. When 30 the clutch is to be reset, the finger-piece 46 on the rod 47 is pushed down, to which rod the setting arm 42 is attached. This arm pushes the pin 43 to swing the arm 44 over 35 to connect the clutch 18 at the same time, the pin 41 of the setting arm 42 engages a recess 48 in the tripping arm 39, and the tripping arm in turn permits the lever 34 to assume its normal position. When the 40 thread is provided with its normal tension, however, this operation does not take place, since the tension on the thread, when the tripping arm 19 is descending with the needle bar, is strong enough to move the 45 sleeve 21 against the light spring 25 and the finger 26 is moved from the path of the tripping arm 19 so that on each descent of the needle bar, the tripping arm 19 descends and rises again without engaging the end 50 of the finger 26, but while the tripping arm is above the finger 26, the tension on the thread is relaxed, due to the take-up that previously took place while the thread was under tension, and the sleeve is thus being 55 constantly swung into and out of the path of the tripping arm 19 according as the tension on the thread is increased and diminished by the operator of the machine.

The device is compact, easily installed on 60 any type of machine now in use, and is positive in its operation.

A setting device for the clutch is thought to be new and provides a means for setting

the clutch again by the operator from the part of the machine adjacent to the needle, which makes it handy to start the machine after arranging the thread which was without tension enough to cause a stopping of the machine.

Having thus described our invention, what we claim is:

1. The combination of a sewing machine having means for disconnecting it from its source of power, with a finger adapted to slide and capable of transverse movement, the finger having a thread guide thereon, a tripping arm operated from the needle bar of the machine and arranged to engage the end of the finger when it is in its normal position, and means in the path of the finger, said means when engaged by the finger acting to operate the disconnecting means, the tension on the thread when the needle bar descends causing the thread to pull the finger from the path of the tripping arm. 8

2. The combination of a sewing-machine having a clutch thereon, with a tripping arm on the needle bar, a finger arranged to slide in the machine, a sleeve in which the finger is mounted, said sleeve being movable transversely to move the finger from the path of the tripping arm, a thread guide on the sleeve, and a clutch-operating mechanism in the path of the finger, the tension on the thread when the needle bar descends acting 9 to move the sleeve and its finger from the path of the tripping arm. 9

3. The combination of a sewing-machine having a clutch thereon, a tripping arm on the needle bar of the machine, the sleeve 10 mounted to swing on the machine frame, a sliding finger in the sleeve, a spring for operating the finger in one direction, the finger being in the path of the tripping arm when in its normal position, a spring acting to hold the sleeve in its normal position, a thread guide on the sleeve, means for holding the clutch in its position to operate the machine, and means operated by the finger for tripping the clutch to permit it to be released, the tension on the thread when the needle bar descends acting to swing the sleeve to move the finger from the path of the tripping arm. 11

4. The combination of a sewing-machine 11 having a clutch thereon, a tripping arm on the needle bar of the machine, a sleeve mounted to swing on the machine frame, a sliding finger in the sleeve, a spring for operating the finger in one direction, the 12 finger being in the path of the tripping arm when in its normal position, a spring acting to hold the sleeve in its normal position, a thread guide on the sleeve, means for holding the clutch in its position to operate the 125 machine, means operated by the finger for

stripping the clutch to permit it to be released, the tension on the thread when the needle bar descends acting to swing the sleeve to move the finger from the path of the tripping arm, and means for resetting the clutch-tripping mechanism to connect the clutch.

In testimony that we claim the foregoing,

we have hereunto set our hands this 13th day of December, 1911.

JOHN WM. ROBERTS.
ARTHUR P. BREWSTER.
